3 Claims. (Cl. 110—101)

This invention relates to stokers for boilers of locomotives and the like. The general object of the invention is to provide feeding and elevating means for carrying the fuel at a lower conveyor level and then elevating it up to the firedoor opening of the boiler on the outside and then deflecting it through the firedoor opening and distributing it over the fire. More specifically, the object of the invention is to provide feeding and elevating mechanism which will leave the firedoor opening area practically unrestricted and open for inspection and hand firing when desired.

A further object of the invention is to provide this feeding and elevating means in simple, durable form, conveniently and unobtrusively placed and occupying a minimum of space.

Other objects of the invention particularly in the structure and combination of the various elements of the feeding, elevating and distributing mechanism will appear from the following description taken in connection with the accompanying drawing, in which

Figure 1 is a vertical sectional view of the feeding, elevating and distributing means illustrating one form of the invention applied to a locomotive boiler;

Figure 2 is a vertical view as seen from line 2—2 of Figure 1; and

Figure 3 is a horizontal plan and sectional view taken approximately on the line 3—3 of Figure 1.

In the embodiment of the invention shown in the drawing, 7 is a locomotive frame; 8 the rear leg or backhead of the boiler firebox; 9 the grate and 10 the firedoor opening, 11 being the locomotive cab deck. These parts are of conventional form and as is well known in the art the boiler at its forward end (not shown) is rigidly secured to the locomotive frame and at its rear end is supported upon the frame 7 by the plate 7a known in practice as the expansion plate which permits the rear leg 8 of the boiler to move fore and aft with respect to the frame during expansion and contraction of the boiler sheets.

Below the level of the cab deck the coal is moved forward from the tender in known manner by the conveyor screw 12 in the conduit 13, and delivered through the universal joint structure designated generally as 14 to the short conveyor screw section 15 on the over-hanging end of the conveyor screw shaft in front of the radial and thrust bearing 16.

The conveyor section 15 is positioned in the entrance end of the expanding elbow 17 rigidly supported at 18 from the frame 7 and flanged

at 19 to receive and support the vertical housing member 120 having at its upper end the distributor plate or guard flange 121 extending into the firedoor opening 10, which is of generally oval formation as best shown in Figures 2 and 3 and which is of the usual size ordinarily employed in boilers to which the coal is hand fired.

Surrounding the outer edge of the firedoor opening is the rim member or firedoor frame 123 fastened in place in any desired manner on the rear surface of the boiler and hinged to the rim member at 125 are the sections 126, 127 of a two piece firedoor forming in effect a hood portion for the housing 120 and constituting as well a deflecting elbow for the coal fed up through the housing. In closed position (Figure 1) the front edges 128 of these door sections rest against the rim member 123 and their lower edges contact the apron flange 129 of the vertical housing 120 so as to form a closed space of hood or elbow formation. The doors 126, 127 are held closed by the pivoted latches 130 and when released the doors may be swung fully open so that the firedoor opening area is free and unobstructed for hand stoking or for inspection of the firebox when desired.

In operation the line of fuel fed through the conduit 13 is received in the elbow 17 and maintained under substantial continuous upward pressure by the feed screw 15 forcing the column of coal upward through the housing 120 so that it overflows at the top and is deflected by the door elbow or hood formation over into the firedoor opening and over the distributor plate or guard flange 121 onto the distributing table 131. It will be observed that the upwardly directed extensions at the opposite sides of the distributor plate or guard flange 121 constitute guard flanges to protect the firebox sheet from the abrasive action of the coal.

To distribute the coal over the surface of the fire a distributor head 132 with the steam nozzles 133 is provided fitting the lower surface of the firedoor opening and protruding inward from under the guard flange 121. Rear arms 134 of the distributing head extend outwardly on each side and steam supply passages are cored through its arms and the head to the nozzle openings 133, the steam being supplied to these passages by pipes 135 controlled by valves 136 one for each nozzle opening. The door sections 126, 127 are preferably provided with observation openings 137 having covers 138. Through either or both of these openings 137 the fireman can observe the fire and distribute the coal

as desired by manipulation of the valves 136 controlling the steam jets from nozzles 133.

The arms 134 of the distributor head are fastened to the lower ends of the rim member 123 and are so shaped as to fit in between the surface of the opening 10 and the lower surface of the guard flange 121. The rim member 123 and the distributor head structure form a complete circuit around the firedoor opening and 10 are stationary with the rear leg structure, the doors 126, 127 being carried by the rim as above described. The vertical housing 120 with its guard flange 121 is independently supported from the frame 7 and clearance is provided for 15 expansion of the boiler which moves the rear fire leg relatively backward. During such expansion the guard flange 121 will protrude further into the firedoor opening, the distributor head 132 being arched as indicated at 140 to 20 permit this relative movement, and the door sections 126, 127 will move back slightly on the housing flange 120.

The distributor plate 131 may be independently supported in place or may be bolted to lugs 25 extending downward from the distributor head as indicated at 141.

In this construction the door elbow or hood formation deflects the coal as it reaches the firedoor level and forces the coal into the firedoor 30 opening to be distributed over the fire. Only a small space is occupied by the feed conduit directly behind the boiler and there is no substantial interference with hand stoking or inspection of the firebox when desired. The opening of 35 the door sections exposes the entire vertical housing and the distributing apparatus so that these parts are then readily accessible for inspection. It will be understood this feed conduit which is the form of an upstanding riser 40 consists of divided upper and lower separable sections, the housing 120 and the elbow 11 forming the lower section and the upper section being formed by the elbow or hood formation comprising the rim member 123 and the door sections 126, 127. Preferably, the feed or riser conduit is disposed centrally on the vertical longitudinal median line of the firing opening 10.

Those familiar with the art will recognize that this invention provides a combined stoker 50 feed conduit and firedoor construction nicely adapted and arranged for use with the conventional size of boiler firing opening such as is in use for hand stoking and further that it is

not necessary with this invention to enlarge the opening for stoker firing.

This application is a division of my application filed September 13, 1927, Serial No. 219,210.

I claim:

1. The combination with a locomotive having a main frame and a boiler having a backhead with a firing opening therein, mounted above the main frame and arranged with the backhead being capable of movement longitudinally with 10 respect to the main frame to accommodate expansion and contraction of the boiler, of a stoker conduit disposed more nearly vertical than horizontal divided horizontally into separable upper and lower sections mounted for 15 relative movement with respect to each other in a direction longitudinal of the locomotive as relative movement between said back head and frame occurs, the upper section communicating with the firing opening and being rigidly secured to the backhead and the lower section fixed rigid with said main frame.

2. The combination with a locomotive having a main frame and a boiler having a rear leg mounted above the main frame and arranged 25 with the rear leg being capable of movement longitudinally with respect to the main frame to accommodate expansion and contraction of the boiler, of an upstanding stoker conduit divided into upper and lower separable sections mounted 30 for relative movement with respect to each other in a direction longitudinal of the locomotive as relative movement between said rear leg and frame occurs, the upper section being fixed to 35 said rear leg to move therewith and the lower section being fixed rigidly with said main frame.

3. The combination with a locomotive having a main frame and a boiler having a rear leg mounted above the main frame and arranged with the rear leg being capable of movement 40 longitudinally with respect to the main frame to accommodate expansion and contraction of the boiler, of an upstanding stoker conduit divided into upper and lower separable sections mounted for relative movement with respect to each other in a direction longitudinal of the locomotive as relative movement between said rear leg and frame occurs, the upper section being fixed to 45 said rear leg to move therewith and the lower section being fixed rigidly with said main frame.

WILLIAM C. PEYTON.
